UNITED STATES PATENT OFFICE.

ALISTER M. RICHARDSON, OF CHARLESTON, SOUTH CAROLINA, ASSIGNOR
TO HIMSELF AND GEORGE B. EDWARDS, OF SAME PLACE.

AUTOMATIC FAN.

SPECIFICATION forming part of Letters Patent No. 325,862, dated September 8, 1885.

Application filed July 3, 1885. (No model.)

To all whom it may concern:

Be it known that I, ALISTER M. RICHARDSON, of Charleston, county of Charleston, South Carolina, have invented a new and Improved Automatic Fan, of which the following is a full, clear, and exact description.

The object of my invention is to provide certain new and useful improvements in the automatic fan, for which United States Letters Patent No. 288,119, were issued to me on the 6th day of November, 1883.

The invention consists, mainly, in pivoting the standard in which the frame is pivoted so as to permit of adjusting the said standard at different inclinations.

Reference is to be had to the accompanying drawings, forming part of this specification, in which similar letters of reference indicate corresponding parts in both figures.

Figure 1 is a front view of my improved automatic fan, parts being broken out. Fig. 2 is an end view of the same, parts being in section.

In the case A two clock-springs, B, are mounted on spindles C, journaled in the sides of the case, and the said springs drive a pinion, D, on the same shaft D', with a cog-wheel, E, engaging with a pinion, F, on the same shaft F', with a cog-wheel, G, engaging with a pinion, J, on a shaft, J', carrying a cog-wheel, K, engaging with a pinion, H, on a shaft H'.

The shafts H' and J' are journaled in one side of the case and in cross-pieces L.

On the inner end of the shaft H' a wheel or disk, N, is mounted, from which a crank-pin, O, projects, to which a connecting-rod, P, is pivoted.

On the shaft H', and on a pivot forming a continuation of said shaft, a standard, Q, is pivoted, which is formed of two pieces diverging toward their lower ends, and each having a circular piece, Q', on the lower end.

Between the upper ends a lever, R, is pivoted, which is connected a short distance from its pivot by the rod P with the crank-pin O.

An aperture is formed in each end of the lever R for receiving the handle of a fan, T, which handle can be held in place by a binding-screw, U.

In place of holding a fan on each end of the lever R, a fan can be held on one end, and a weight, V, on the other end.

As the shafts H' J' do not extend entirely across the case, a larger fly-wheel, N, can be mounted on the inner end of the shaft H', and thus a very regular movement is obtained.

W is a guard to prevent the springs B from binding or pressing against the shaft D' when they expand.

The operation is as follows: The spring B revolves the wheel N, and from the same the lever R is swung up and down. The fans T create a very pleasant breeze. As it is frequently necessary and desirable to have them deliver cool air at a certain spot or place—for example, in sick-rooms—it is very desirable to have the standards Q adjustable. The said standards can be swung to the right or left, as may be desired, without interfering with the operation, as the shaft of wheel N and the turning point of the standard Q are the same.

The standard Q can be locked at the desired inclination by a latch, a, on one of the bars of the standard, and engaging with one of the sides of the casing.

Having thus described my invention, I claim as new and desire to secure by Letters Patent—

1. The combination, with a case, springs, and a train of gearing in the same, of a driving-wheel operated by the train of gearing, standards mounted to swing concentrically with the driving-wheel, a rocking arm for carrying one or more fans pivoted to the standard, and a rod for operating the rocking arm from the driving-wheel, together with a latch or retaining device to hold the standard at its point of adjustment, substantially as herein shown and described.

2. The combination, with the case A, of the short shafts H' J', the cross-pieces L, a train of gearing in the case A, the wheel N on the shaft H', the pivoted standard Q, the lever R, pivoted on the same, and the rod P, for connecting the lever R with the wheel N, substantially as herein shown and described.

ALISTER M. RICHARDSON.
